UNITED STATES PATENT OFFICE.

HARRY W. CLIFTON AND GEORGE CLIFTON, OF KANOPOLIS, KANSAS.

STORAGE-OIL-TANK PROTECTOR.

1,233,028.

Specification of Letters Patent. Patented July 10, 1917.

Application filed April 7, 1916. Serial No. 89,697.

To all whom it may concern:

Be it known that HARRY W. CLIFTON and GEORGE CLIFTON, citizens of the United States, residing at Kanopolis, in the county 5 of Ellsworth and State of Kansas, have invented new and useful Improvements in Storage-Oil-Tank Protectors, of which the following is a specification.

This invention relates to protectors 10 against fire especially adapted to be used upon storage oil tanks and it consists in the novel features hereinafter described and claimed.

An object of the invention is to provide 15 a protector of the character indicated which is of simple and durable structure and which will effectually protect the tank against fire caused by lightning or explosion or any other cause of ignition.

20 With this object in view the structure includes a series of doors or lids hingedly mounted at the uppermost portion of the top of the tank and which normally lie over openings provided in the said top. The 25 said doors or lids are so arranged that an excess of pressure within the tank may escape through the openings under the free edge portions of the doors or lids but under normal conditions the said doors or lids 30 remain closed whereby the contents of the tank is protected and the entrance of foreign substances into the tank prevented. In the event of sudden creation of pressure within the tank incident to fire or explosion 35 the doors or lids may be forced open by the pressure thus relieving the tank and contents of the same but as soon as the pressure is reduced to normal the said doors or lids close automatically and thus shut off the 40 external air sufficiently to extinguish any fire which might remain in the tank.

In the accompanying drawings:—

Figure 1 is a top plan view of the invention.

45 Fig. 2 is a detailed sectional view of one of the doors.

Fig. 3 is a sectional view of a portion of the tank cut on the line 3—3 of Fig. 1.

The tank to which the device is applied 50 has the usual cylindrical body 1 which is provided with a cone shaped top 2. The top 2 is provided with a series of openings 3 which are arranged in the form of a circle and spaced from each other. The arrangement of the openings 3 is concentric with 55 the center of the top and the said openings

are spaced from the peak or center of the said top. A hinged door or lid 4 is arranged to normally lie in an inclined position over each of the openings 3. 60

Each opening 3 is surrounded by a combing 5 and the door 4 is hinged at a point between its opposite side edges and below its under face to one side of the said combing. The top 2 of the tank is provided with 65 openings 6 which are located beyond the opposite side of the combing. Rods 7 are attached to the free edge portion of the door 4 and pass through the openings 6. Coil springs 8 surround the said rods 7 and 70 bear at their upper ends against the under surface of the top 2. The lower ends of the springs 8 bear against heads 9 carried at the lower end portions of the rods 7. The springs 8 are under tension with a 75 tendency to hold the doors 4 in closed positions over the combings 5 and openings 3.

Ducts 10 lead in from the sides of the body 1 and extend up along the under surface of the top 2 and the upper ends of the 80 said ducts terminate above the upper edges of the openings 3 and in the vicinity of the peak or highest point of the top 2.

In the event that the said tank is struck by lightning or an explosion should take 85 place therein from any other cause the excessive pressure created within the tank will escape from under the free edges of the doors or lids 4 by lifting them and as soon as the pressure within the tank assumes 90 its normal condition the said doors 4 will close whereby the external air is shut off from the interior of the tank and any fire which might remain in the tank is extinguished inasmuch as the source of oxygen 95 is cut off through the openings 3. Thus the excess of pressure created within the body of the tank escapes therefrom by lifting the free edge portions of the doors 4 and as soon as the pressure within the tank 100 assumes normal the said doors 4 close. The ducts 10 prevent the accumulation of gas under excessive pressure in the upper portion of the tank inasmuch as when the gas begins to accumulate and assumes compression it is forced through the ducts 10 out of the tank. Thus under normal conditions 105 the excessive gas pressure may escape from the tank without lifting the doors 4.

When the doors 4 assume closed positions 110 following an explosion of the gas in the tank the smoke which may be trapped in

the tank passes out through the ducts 10 and extinguishes any flame which may remain at the outer ends of the said ducts.

Having described the invention what is claimed is:—

An oil tank having a conical roof provided with an opening located at a point below the highest point of the roof, a spring retained door hinged to the roof and normally closing said opening, and a duct leading into the tank at the side thereof at a

point below the roof and extending in an inclined position under the roof and terminating at its inner upper end at a point beyond the upper edge of the roof opening. 15

In testimony whereof we affix our signatures in presence of two witnesses.

HARRY W. CLIFTON.
GEORGE CLIFTON.
